UNITED STATES PATENT OFFICE.

FRANK SPRADER, OF WEST ALLIS, WISCONSIN.

DESIGN FOR A BUTTER-CUTTING GAGE.

59,691.

Specification for Design.

Patented Nov. 15, 1921.

Application filed June 24, 1921. Serial No. 480,238. Term of patent 3½ years.

To all whom it may concern:

Be it known that I, FRANK SPRADER, a citizen of the United States, residing at West Allis, in the county of Milwaukee and State of Wisconsin, have invented a new, original, and ornamental Design for a Butter-Cutting Gage, of which the following is a specification, reference being had to the accompanying drawing, forming part thereof.

Figure 1 is a side elevation of a butter cutting gage showing my new design.

Fig. 2 is a plan view of the same.

Fig. 3 is an end elevation of the same.

I claim:

The ornamental design for a butter-cutting gage, as shown.

In testimony that I claim the foregoing I have hereunto set my hand at Milwaukee, in the county of Milwaukee and State of Wisconsin.

FRANK SPRADER.
